UNITED STATES PATENT OFFICE.

FRANK E. SEELEY, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

PLURAL SOCKET.

1,107,120.

Specification of Letters Patent.

Patented Aug. 11, 1914.

Application filed November 21, 1912. Serial No. 732,712.

To all whom it may concern:

Be it known that I, FRANK E. SEELEY, a citizen of the United States of America, and residing at Bridgeport, in the county of 5 Fairfield and State of Connecticut, have invented a certain new and useful Improvement in Plural Sockets, of which the following is a specification.

My invention relates to plural sockets and 10 particularly to twin sockets, the object of my invention being to provide an improved device of this character provided with a switch mechanism by means of which the circuits of the several sockets in the fitting 15 may be controlled.

In the accompanying drawing in which my invention is illustratively embodied, Figure 1 is a side elevation of a twin socket mounted on a pipe end and provided with a 20 pull switch; Fig. 2 is a plan view of the same with the casing removed; Fig. 3 is a face view of one of the insulating buttons with some of the metal parts attached; Fig. 25 4 is a similar view of the other insulating button; Figs. 5 and 6 are cross sections showing the switched center contacts for the two lamp sockets; Fig. 7 is a cross section showing the connection from one of the wire terminals to the switch spindle and rotary 30 switch element; Fig. 8 is a perspective of the rotary switch element; and Fig. 9 is a side elevation showing a combined twin socket and attachment plug in which my invention 35 is embodied; Fig. 10 is a more or less diagrammatic plan of the button A as in Fig. 3, to show the relative positions of the switch piece 28 with relation to the terminals 33 and 37.

The present invention in the form shown, 40 comprises a twin socket having a casing comprising separable ends 10 and 11 sleeved together over the switch mechanism and lamp terminals and united by means of co-operating latching elements 12 and 13 in 45 well understood manner. Upon one end of the casing a boss 14 is formed which is provided with a threaded nipple 15, by means of which the fitting may be mounted upon the threaded end of a wire conduit 16 or the like. Within the casing are housed insulating buttons A and B, on the outer faces of 50 which are mounted the lamp-receiving shells 17 and 18. Between the opposed faces of the buttons A and B which are spaced apart 55 by standards 19 and 20, threaded to receive

the binding screws 21, 22, the switch mechanism hereinafter described is mounted. A third spacing member 23 carries a bell 24 through which the switch operating chain 25 is guided out of the casing.

The particular switch mechanism employed to control the lamp socket circuits is immaterial. As here shown both of the 60 socket shells 17 and 18 are constantly in the switch circuit, by reason of their direct connection to the standard 20. The center contacts 26 and 27 are brought into the circuit through a rotary switch member 28 which takes its current from its bearing bushing 29, the latter in turn receiving the current 65 from the standard 19 through the angled lug 30 of the latter. The center contact 26, co-operating with the shell 17, to form one 70 socket, is electrically connected through a screw bolt 31 with an angled terminal 32 which carries a spring contact piece 33 lying 75 against the periphery of the ratchet 34 over which the contact wings of the rotary switch member 28 are angled. The center contact 27, co-operating with the shell 18 to form the 80 other lamp socket, is connected through a bolt 35 to the spring terminal 36 which likewise carries a spring contact piece 37 bearing 85 against the periphery of the ratchet member 34 at a point substantially 90° from contact element 33 of the terminal for the center contact 26.

As noted in Fig. 7 the rotary switch element 28 comprises a central disk portion with stud-bearing 38 with two peripheral 90 contact wings 39 spaced 90° apart and in assembled condition overlying two adjacent teeth of the four toothed ratchet block 34 of insulating material. Consequently upon the rotation of the latter, the current conducted 95 through the rotary contact 28 is distributed first to the terminal 26, and then simultaneously to both terminal 26 and 27, and thirdly, to center contact 27 alone, and finally breaks the connection altogether so 100 that both lamps are out of the circuit. It is thus possible to have either lamp alone, or both lamps simultaneously lighted, as may be desired. To operate the rotary contact 28, I provide a disk 40, the down-struck lugs 41 of 105 which engage in one face of the insulating block 34. A central spindle 42 fast with the disk 40 projects from its opposite face and is journaled in the socket of the spring-adjusting abutment 51. Ratchet teeth 43 110

are pressed out from this face of the disk to engage coöperating pawl teeth 44 formed on the disk 45, the latter being journaled on the spindle 42 and carrying a chain rail 46 of any suitable type. A coil spring 47 presses the pawl disk 45 into engagement with the ratchet disk 40, while the engagement between the extended end 48 of the spring and the tongue 49, struck from the ratchet plate, serves to return the latter to initial position after actuation by the pull chain. The other end of the spring is engaged by one or the other of the lugs 50 formed on the abutment 51, by the rotarial adjustment of which the tension of the spring may be varied.

It is obviously possible to not only vary the switch mechanism to differently control the lamp circuits but to mount the switched sockets upon an attachment plug, as suggested in Patent 1,010,984, granted to me jointly with George B. Thomas, and I do not limit myself to the precise details of the construction shown, but

26 I claim as my invention:—

1. A twin socket having a pair of insulating buttons spaced apart, lamp terminals on the outer faces of said buttons and a pull switch mounted between the opposed faces 30 of said buttons, in combination with an in-closing casing comprising independent shells

respectively sleeved over said insulating buttons and the lamp terminals thereon, latching means for engaging the adjacent ends of said shells together, a bell mouth outlet 35 through said casing for a flexible pull member for operating the switch and a threaded nipple projecting from said casing for securing the fitting to a fixture, substantially as described.

2. A twin socket having an insulating body element, oppositely faced lamp sockets arranged in substantial alignment on said insulating body, a pull switch carried by said insulating body 45 and electrically interposed between said lamp sockets, in combination with an in-closing casing comprising independent shells sleeved over said body and sockets, latching means for engaging the adjacent ends of said shells together, an outlet 50 through the casing for a flexible pull member for operating the switch and an outwardly projecting threaded element for securing the fitting to a fixture.

In testimony whereof I have signed my name to this specification, in the presence of two subscribing witnesses.

FRANK E. SEELEY.
